COMBINED HEADING AND TRIMMING MACHINE

Application filed November 2, 1928. Serial No. 316,854.

This invention relates to a combined heading and trimming machine, and is adapted particularly to the manufacture of bolt blanks.

5 The present method of forming a head on a bolt of the machine bolt type, which is usually square or hexagonal in shape, is to first make a blank by upsetting or heading one end of a length of wire, and then to trim the head to the proper size and shape. These operations heretofore have been performed upon 10 separate machines, with the attendant intermediate handling.

One of the objects of the present invention 15 is to combine in a single machine the two operations of upsetting and trimming.

Another object of the invention is the provision of a machine in which the two aforesaid operations are performed in approximately 20 the same length of time that has been required heretofore for the performance of one of them.

A further object is the provision of a machine in which the striking movement of the 25 machine slide serves to upset one blank and at the same time to trim the head of the blank which was upset by the next preceding stroke of the slide.

Still another object is the provision of a 30 compact and simple finger mechanism for transferring blanks.

Other objects and features of novelty will appear as I proceed with the description of 35 that embodiment of the invention which, for the purposes of the present application, I have illustrated in the accompanying drawings, in which,

Figure 1 is a side elevation of the machine, certain of the parts being removed and others 40 shown in section to more clearly illustrate the invention.

Figure 2 is a view partly in section on the line 2—2 of Figure 1, showing the transfer finger and associated parts.

45 Figure 3 is a horizontal sectional view showing a double cam by means of which the movements of the finger mechanism are produced, the section being taken on a line corresponding to the line 3—3 of Figure 1.

50 Figure 4 is a large scale vertical sectional

view taken substantially on the line 4—4 of Figure 1, illustrating the finger mechanism.

Figure 5 is a detail sectional view taken on the line 5—5 of Figure 4.

Figure 6 is a front elevational view on a 55 larger scale of a portion of the finger operating mechanism.

Figure 7 is a plan view in somewhat dia- 60 grammatic form, illustrating certain features of the invention, and

Figure 8 is a detail elevational view of the 65 knife which severs the material and carries it into position for heading.

In the drawings a portion of the frame of the machine is indicated at 10. In the frame 65 is journaled a main shaft 11, rotated in any suitable manner, and adapted to reciprocate a heading slide 12, by any known means, such for instance as an eccentric and connecting rod or Scotch yoke. 70

In the heading slide 12 I mount a hammer 75 13, and spaced somewhat therefrom and preferably directly below the hammer I mount a trimming die 14, the latter being hollow and capable of discharging the trimmed blanks through its rear end. In a stationary part of the machine opposite the heading slide 12 there is a die block 15, in which is mounted a heading die 16, the opening in the die being in alignment with the passage 17 in the bed of the machine. Adjacent the block 15 there is also secured in the bed of the machine a bracket 18, carrying a hollow punch 19, the opening in the punch being in alignment with the passage 20 in the bracket, which, in turn, is in alignment with a larger passage 21 in the bed of the machine. 80

If desired, the parts 15 and 18 may be constructed to be inserted or withdrawn from the machine as a unit. The opening in the punch 90 19 is of the proper size to admit the shank of the blank, and the working surface of the punch is formed of the desired size and shape of the head of the finished blank, that is, it corresponds in size and shape with the desired cross-section of the blank head. The punching die 14 has an interior surface shaped to fit the punch 19 and is in alignment therewith. 95

The knock-out mechanism for die 16 com- 100

prises a knock-out rod 22, slideable in passage 17 and having a forward extremity adapted to enter the opening of the die and eject the blank therefrom. The rear end of the rod 22 is adapted to be engaged by a knock-out lever 23, whose motion in one direction is limited by an adjustable stop 24 which may be locked in any desired position by a nut 25. In order to operate the lever 23 I employ a rod 26 which is threaded into the heading slide 12, as shown in Figure 7, extends through an opening in the lever 23 and is provided with a sleeve 27 which may be adjusted to the proper position upon the rod by means of a nut 28 carried by the sleeve and locked in adjusted position by a lock nut 29. At the proper moment in the receding movement of the slide 12 the sleeve 27 engages lever 23 and causes the latter to push upon the rod 22, thereby 20 ejecting the blank from the die 16.

Wire material enters the machine through a pair of feed rolls, one of which is shown at 30 in Figure 7. The mechanism for driving these rolls intermittently is not illustrated 25 herein as it is entirely conventional and well understood in the art. The required length of wire 31 is fed through a passage in the bed of the machine into the position indicated in Figure 7, the length of exposed wire being 30 determined by a stop 32 of ordinary construction and operation, which swings out of the way of the slide when its work is completed.

The measured wire 31 is then cut off by a knife 33, which carries spring fingers 34, by 35 means of which the material is grasped and held after the cut is made. The knife 33 is mounted in a cross-slide 35 which is movable in guides 36, and carries on its lower side an anti-friction wheel 37 that is engaged by the 40 walls of a cam groove 38 formed in a slide block 39. This block is reciprocated once for each cycle of the machine through a connecting rod 40 from an eccentric 41 upon the cam shaft 11. Obviously the knife 33 is caused to 45 move in and out transversely of the machine through the mechanism described. Its inward movement is sufficient to carry the severed wire material from the position shown in Figure 7 to a position directly in front of 50 die 16.

Coming now to the finger mechanism by means of which I transfer blanks ejected from the die 16 into position to be acted upon by the trimming tools, it will be noted that 55 upon the end of the shaft 11 opposite to that which carries eccentric 41, there is a disc 42 in the rear face of which are formed two cam grooves 43—44 (the plate 42 is removed from Fig. 1 in order to disclose other parts.) Cam 60 followers 45 and 46, respectively, run in the grooves 43 and 44, these followers being mounted upon levers 47 and 48, which are pivoted at 49 and 50 to a bracket 51 secured to the frame of the machine.

65 On their lower ends the levers 47 and 48

carry arms 52 and 53, which are pivoted at 54 and 55 to the levers, and the forward ends of which may be swung up or down for adjustment purposes by threaded rods 56 and 57. To the forward ends of these adjusting arms 70 52 and 53 are pivotally connected links 58 and 59 which extend forward to the position shown in Figure 1. The link 58 is pivoted at its forward end to a crank 60 that is fixed to the outer extremity of a rock shaft 61. The rear end of the shaft 61 is journaled in a bracket 62, which is secured by any suitable means to the frame 10 of the machine. The forward end of the shaft extends through and is supported in an independently revoluble sleeve 63 provided with a pinion 64 on its rear end and a pinion 65 on its forward end just behind the crank 60. Meshing with the pinion 65 is a sector 66 which swings upon a pintle 67 mounted in the bracket 62. 75 The sector 66 is pivotally connected to the forward end of link 59, by means of which it is adapted to be oscillated.

The pinion 64 meshes with a vertically arranged rack 68, to the upper end of which 90 is fixed a finger holder 69. An elongated pinion 70 is mounted for rotation in the bracket 62, being arranged parallel to the rack 68 and preferably in rather close proximity thereto. Within a hollow portion of the bracket 62 the shaft or pinion 70 carries a spiral gear 71 which meshes with a second spiral gear 72 that is fixed upon rock shaft 61. The pinion 70 extends through an opening in the finger holder 69, being free to turn with respect to the holder and constituting a guide for the holder as the latter moves up and down.

The holder 69 is provided with an inclined guide-way in which is mounted to slide a 105 rack 73, that carries on its free end the transfer finger. The finger itself may comprise a rigid piece with a V-slot 74 in its free end and a pair of levers 75 which are beveled off and hooked at their forward ends in order to properly grasp the work. These levers are pivoted to the rigid portion of the finger at the points 76, and their rear ends are resiliently forced apart by a coil spring 77 or the like.

Operation

The wire material enters the machine in the usual manner, being fed by the rolls 30 until it strikes the movable stop 32. The cross slide 35 then advances, cutting off the exposed length of wire and moving further inwardly until the severed length of wire stands directly in front of the die 16. The slide 12 in the meantime has advanced upon its operating stroke and now engages the outer end of the material, starting it into the die. Thereupon the cross slide 35 is retracted rapidly, the fingers 34 springing back to clear the material.

Further forward movement of the slide 12 causes the hammer 13 to force the wire 31 as far as it will go into the die 16 and then to upset the outer end of the wire to form a head. 5 The blank being thus formed, the slide 12 starts on its return stroke. During this stroke the sleeve 27 on rod 26 engages lever 23 and the latter pushes upon rod 22, forcing the blank out of the die 16. Before the 10 ejection of the blank is completed, however, the transfer finger moves inwardly causing the hooks on the end of levers 75 to ride over the shank of the blank and grip the same against the sides of the V-slot 74. The rack 68 is 15 then actuated by the pinion 64, so as to move vertically downward, carrying the blank into position in front of the trimming punch 19. Again the slide 12 advances and the trimming die 14 strikes the head of the blank 20 forcing the shank of the latter into the opening of the punch 19. When the blank is thus engaged the pinion 70 of the finger mechanism rotates and operates through rack 73 to withdraw the transfer finger. When the 25 finger is out of the way further forward movement of the slide 12 drives the blank into the punch 19 until the head of the blank engages the end of the punch. Thereafter the final movement of the slide causes the die 14 to 30 move over the end of the punch 19, and the head of the blank is thereby trimmed. The engagement between the die 14 and the head of the blank being very snug, the trimmed blank remains in the die 14 as the slide 12 35 moves backwardly. This blank is forced through the hollow die 14 on the next operating stroke of the slide by the blank then in the punch 19. A suitable hopper or container (not shown) receives the trimmed blanks as 40 they drop from the die 14.

With regard to the finger mechanism it may be remarked that the rack 68 and pinion 70 may be operated one at a time so as to produce movement of the finger either 45 vertically or in the line of the rack 73, or if desired, the rack 68 and pinion 70 may be operated simultaneously so as to bring about what might be termed a composite movement of the finger, it being possible to obtain any desired movement by properly laying out the 50 cam grooves 43 and 44. It will also be obvious that the rack 73 may be arranged at a right angle to the pinion 70 if desired.

While in the foregoing description and in 55 the drawings I have disclosed more or less in detail one embodiment of the invention, such detailed disclosure is not to be construed as a limitation of the invention.

Having thus described my invention what 60 I claim is:

1. In a machine for heading and trimming bolt or screw blanks having straight-sided heads, two blocks relatively reciprocable, a heading die and a hollow trimming punch 65 mounted in one of said blocks, a heading

hammer and a trimming die mounted in the other block, means for producing relative reciprocation of said blocks, means for ejecting a blank from said heading die and inserting another blank between hammer strokes, 70 means for transferring the headed blank to said trimming punch while said blocks are separated, the head of each trimmed blank remaining in said trimming die as the blocks recede from each other and acting as a ram 75 for pushing the succeeding blank into the hollow trimming punch as the blocks approach each other.

2. In a machine for heading and trimming bolt or screw blanks having a straight-sided heads, a trimming die hollow throughout its length, a hollow punch mounted in alignment therewith adapted to receive the shank of the blank, means adapted to position the blank between said tools in proximity to said punch while the tools are separated, and means for producing relative reciprocation between said die and punch adapted to cause the blank head to enter the die only, whereby the head of a blank remains in the die and the shank protrudes therefrom after each blow and said protruding shank acts as a ram for pushing the succeeding blank into the hollow punch as the tools approach each other.

3. In a combination bolt heading and trimming machine, a trimming die through which the blank is to be driven endwise, a hollow punch operatively associated with said die, means for causing relative movement of said punch and die, said punch being adapted to 100 push a blank into the die and then recede leaving the shank of the blank projecting from the die, a transfer finger adapted to grasp a headed blank and position the same between said projecting shank and said hollow punch when the latter are in their separated positions, the projecting shank of the first blank being adapted to push the second blank into the hollow punch, after which the second blank pushes the first blank through 110 said die.

In testimony whereof, I hereunto affix my signature.

ROY H. SMITH.
